UNITED STATES PATENT OFFICE.

JACOB EVERETTE DODD, OF YOAKUM, TEXAS.

BABY-PROTECTOR.

Specification of Letters Patent. Patented Sept. 16, 1913.

1,073,478.

Application filed September 13, 1912. Serial No. 720,224.

To all whom it may concern:

Be it known that I, JACOB E. DODD, a citizen of the United States, residing at Yoakum, in the county of Dewitt and State 5 of Texas, have invented new and useful Improvements in Baby-Protectors, of which the following is a specification.

This invention relates to baby protectors, the object in view being to provide a simple 10 device adapted to be easily applied to an infant, and which when properly applied will prevent the child from bending his elbow sufficiently to enable the hands to reach the mouth.

15 By means of the device hereinafter described, the child is at liberty to play and move about or crawl from place to place, while at the same time the child is prevented from placing articles, too numerous to mention, in the mouth. This affords great relief to the mother or person caring for the child.

With the above and other objects in view, the invention consists in the construction, 25 combination and arrangement of parts, as will be hereinafter more fully described, illustrated in the accompanying drawings, and pointed out in the claim hereunto appended.

30 In the drawings: Figure 1 is a perspective view of the complete device. Fig. 2 is a view illustrating the device applied to an infant.

The device comprises essentially a pair of 35 sleeves 1, comparatively inflexible and composed of some such material as card-board for example. Each sleeve is of a suitable diameter and length to receive one of the arms of the infant and cover the elbow, the 40 length of the sleeve preventing excessive bending of the elbow, such as would be necessary to enable the hands to reach the mouth. At its outer end, each sleeve is preferably rolled, as shown at 2, to avoid 45 injury to the arms of the infant, while at its opposite or upper end, each sleeve is provided with an eye 3, in which is received a link 4. The link 4 is substantially rectangular with an open center, and the eye 3 is an 50 integral part of the sleeve, being formed by

providing said sleeve with a longitudinally projecting tab which is rolled over one of the side bars of the link and terminally fastened, as by glue, to the body of the sleeve, as indicated in Fig. 1. The two sleeves are 55 connected together by means of a back strap 6 which is adjustable in length by means of a suitable buckle 7 of ordinary construction, the extremities of the strap being looped around the outer bars of the links 60 and sewed or otherwise secured to the body of the strap, as shown at the right of Fig. 1.

Secured about centrally to the back strap 6 is a ring 8, to which a safety pin 9 may 65 be connected for fastening the back strap to the clothing of the infant. Said ring is also adapted to receive a ribbon or tape, forming the neck band 10 which may be passed around the neck of the infant and 70 tied in a bow or knot, or fastened in any convenient manner, the said neck band also serving as a support to prevent the back strap from falling down the back of the infant. Either or both of said devices may 75 be used for holding the back strap in position, and this insures the retention of the elbow covering sleeves in proper position.

From the foregoing description, taken in connection with the accompanying drawings, 80 it will be seen that the inflexible sleeves 1 prevent the infant from bending his elbows, so as to place articles of various kinds in the mouth. At the same time, in crawling these inflexible sleeves assist the infant 85 by bracing the arms. The device as a whole does not interfere in any way with the normal and proper movements of the infant, but only comes into play when the infant attempts to put an article of any kind into 90 his mouth.

What is claimed is:

A baby protector, comprising a pair of inflexible sleeves adapted to cover the elbows and prevent excessive bending of the 95 same, eyes at the upper extremities of said sleeves formed by rolling over portions of the top edges of the sleeves, open center links, one bar of each of which is journaled to turn in one of said sleeves, an adjustable 100

back strap terminally looped around the opposite bars of said links and connecting said sleeves together, an eye fastened to the central part of the back strap, and a retaining device passing through said eye and adapted to suspend the back strap at a single point centrally of the back of the neck.

In testimony whereof I affix my signature in presence of two witnesses.

JACOB EVERETTE DODD.
